Attn:

UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

POURING SPOUT.

Application filed June 6, 1921. Serial No. 475,329.

This invention relates in general to spout and nozzle cans, and has more particular reference to the provision of a spout adapted to embrace the nozzle or pouring neck and be moved from a position protruding over the side of the can to a position within the periphery of its top wall.

A principal object of the invention is the provision of a spout which may be readily arranged in pouring position and which, when so arranged, may be rendered substantially non-leaking so that the material pouring from the nozzle across the spout cannot run down and be distributed over the top of the can.

The invention has for a further important object the provision of a spout of this character and of sheet metal, which may be cheaply constructed and assembled with the can itself, and which will be readily removable. The invention contemplates in this regard a spout consisting merely of a sheet of metal given a spout formation with a hole for receiving the nozzle, the construction of the parts being such that the complete assembling may be accomplished by pressing the spout down by hand over the nozzle.

The invention has for a purpose also the provision of a spout, the parts of which are so constructed and arranged that the spouts may be supplied to the packer separate from the nozzle and be positioned by him in place thus effecting economy of packaging the cans by the can manufacturer.

Numerous other objects and advantages of the invention will be apparent as it is better understood from the following description, which, taken in connection with the accompanying drawings, discloses a preferred embodiment thereof.

Referring to the drawings,

Figure 1 is a top plan view of a can embodying my present invention; and

Fig. 2 is a partial side elevation and partial section of the same.

For the purpose of illustrating my invention I have shown on the drawing a can of any usual or preferred construction having a top wall 12 provided with a nozzle receiving opening 13. About this opening is provided an upstanding flange 14 which is embraced in a crimped seam 15 by the edge of the nozzle. This nozzle comprises in the

present instance a neck having an upper threaded part 16 and a lower tapered or conical part 17 from which the threads are absent. Beneath the tapered part 17 is a horizontally extending flange 18 which terminates in the edge seamed at 15. The spout comprises a sheet of metal formed into the pouring mouth 19 and provided with an opening 21 adapted to fit down on the tapered neck portion 17. The spout may, if desired, be provided with a short flange 22, the usual cap being indicated at 23.

The spout is adapted to be pressed down into firm engagement with the tapered part of the neck and by reason of this taper produces a tight fit so that leakage down around the nozzle is reduced to a minimum if not entirely eliminated.

The upstanding seam 15 provides a valley or depression between itself and the nozzle proper in which any small amount of material leaking through may be confined. The spout may be readily rotated to a pouring position by moving it up along the taper slightly and when in pouring position pressed down therealong.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a can, the combination of a sheet metal nozzle having a screw-threaded portion and below the same a tapered spout-supporting portion, a spout adjustable and having an aperture of a size to wedge thereon, and a cap screwed on said nozzle and constructed to engage said spout and force it on said tapered portion.

2. In a can, the combination of a sheet metal nozzle having a screw-threaded portion and below the same a tapered spout-supporting portion, and a spout having a flange extending parallel with the nozzle and having an aperture of a size to wedge on and fit tightly along said tapered portion after adjustment thereon.

3. A can, comprising a body, a nozzle having a tapered neck and secured to the body in a seam extending up and providing a depression between said neck and said seam, and a spout embracing the taper of said neck.
4. A can, comprising a nozzle having a tapered neck, and a spout embracing the ta-
- per of said neck, said spout having an aperture of a size to wedge on said taper and being adapted to be moved up to a free position and rotatable about the nozzle and moved down into tight engagement at pouring position.

JOHN M. HOTHERSALL.
